UNITED STATES PATENT OFFICE.

JOHN J. BOOKHOUT AND JAMES R. BOOKHOUT, OF DALLAS, TEXAS.

UNDERREAMER.

Application filed December 2, 1921. Serial No. 519,497.

To all whom it may concern:

Be it known that we, JOHN J. BOOKHOUT and JAMES R. BOOKHOUT, citizens of the United States, residing at Dallas, in the county of Dallas and State of Texas, have invented certain new and useful Improvements in Underreamers, of which the following is a specification.

This invention relates to new and useful improvements in underreamers.

The object of the invention is to provide an underreamer having expanding cutters arranged to travel over arcuate expanding surfaces which also provide solid supports for the cutters when expanded. Another feature resides in the arrangement whereby the shanks of the cutters are firmly seated when said cutters are expanded and held against displacement.

Another object of the invention is to provide ample bearing surfaces to sustain the upward thrust of the cutters and prevent breakage. A further object is to produce an underreamer which may be connected at its lower end with a suitable drilling tool so that the two may be used in conjunction and operated in the hole at the same time or either used without withdrawing from the hole to connect the desired tool to the cable.

An advantage of this tool is that an adequate casing seat is formed and a "rat-tail" or advance hole is drilled, whereby danger of setting the casing into the oil sand is obviated. Another advantage is the formation of a straight hole from top to bottom. By drilling and underreaming at the same time, danger of collapsing of the well walls in soft formations is obviated, because the casing can be lowered immediately following the underreamer.

A construction designed to carry out the invention will be hereinafter described together with other features of the invention.

The invention will be more readily understood from a reading of the following specification and by reference to the accompanying drawings, in which an example of the invention is shown and wherein:

Figure 1 is an elevation of an underreamer constructed in accordance with our invention.

Fig. 2 is a longitudinal sectional view of the same,

Fig. 3 is a cross-sectional view taken on the line 3—3 of Fig. 2,

Fig. 4 is an enlarged elevation of a portion of the underreamer, the cutters being retracted,

Fig. 5 is a detail showing the stem,

Fig. 6 is a similar view at right angles to Fig. 5,

Figs. 7, 8 and 9 are details in elevation of one of the cutters,

Fig. 10 is a plan view of one of the cutters,

Fig. 11 is an underside view of the same,

Fig. 12 is a detail in elevation of one cutter expanding and supporting plate,

Fig. 13 is an elevation of the inner side of the same,

Fig. 14 is a cross section on the line 14—14 of Fig. 12, and

Fig. 15 is a vertical section on the line 15—15 of Fig. 12,

In the drawings the numeral 20 designates a cylindrical stock or body having a central bore 21 extending downwardly from its upper end. A central stem 22 depends from the lower end of the stock and is preferably integral therewith. The bottom of the stock is under cut so as to form an annular inwardly and upwardly inclined socket 23. The outer edge of the socket is surrounded by a radial lip 24, which provides a flat annular bearing surface and obviates a sharp wedge-shaped edge.

The lower end of the stem is provided with a tapered screw-thread 25 adapted to enter a socket 26 in a coupling 27. The upper end of the coupling is formed into an upwardly and outwardly inclined annular seat 28. Between the socket 23 and the seat 28 a pair of segmental plates 29 are engaged, their ends being shaped to fit the said socket and seat. The upper end of each plate has a marginal shoulder 30 engaging the flat lip 24. These plates fit snugly around the stem and have their vertical edges in contact. By screwing the coupling onto the stem the plates are firmly fastened in place.

Below the lip 24 the stem has a transverse slot 31 and a reduced bore 32 extends from the upper end of the slot to the bore 21. A mandrel 33 is mounted to slide snugly in the bore 32 and projects into the slot 31 and the bore 21. A coiled spring 34 surround-

ing the mandrel rests on the shoulder at the bottom of the bore 21 and engages under a head 35 on the upper end of the mandrel, whereby said mandrel is resiliently supported.

Each plate 29 has in its outer side a recess provided with an outwardly and upwardly extending curved face 36, presenting a broad bearing surface transversely of the 10 plate. At the upper end of each face, is an overhanging radial shoulder 37 and each face at its lower end terminates at a transverse groove 38 from the lower edge of which a downwardly inclined ledge 39 extends. In the upper central portion of each face 36 a vertical slot 40 is formed and is extended inwardly thru the shoulder 37. This gives each slot an upwardly and inwardly inclined outer wall 41 with a shoulder 42, at its upper end, as is best shown in 20 Fig. 15.

A segmental cutter blade 43 has an arcuate outer face provided with an extended cutter 44 at its lower edge. This cutter is 25 illustrated in detail in Figs. 7 to 11 inclusive. The cutter has a central shank 45 extending upwardly from its upper rear portion and also has a curvilinear inner face 44' conforming to the radius of the face 36 30 of each plate 29. Each cutter has its outer face cut back, whereby the cutter is reduced in thickness upwardly; and also whereby a riding surface for engagement with the wall of the casing is provided when the cutter is 35 moved down into the groove and withdrawn as is shown in Fig. 4.

Each shank 45 has a reduced inwardly extending lug 46 at its upper end of such width as to fit snugly in the slot 31. The 40 mandrel has a cross bar 47 at its lower end engaging on each side under one of the lugs 46. The mandrel has notches immediately above the bar for receiving the lugs (Fig. 2). The stem 22 has curved guides 48 into 45 which the slot 31 opens. The inner vertical faces of the shanks ride in the guides, while the curvilinear faces 44' ride on the faces 36.

The stock 21 has a threaded tapered pin 49 at its upper end whereby it may be connected with a sub or the like for suspension at the end of a cable. A transverse slot 50 extends thru the stock at the upper end of the bore 21. A wedge tool 51 (Fig. 6) inserted in said slot engages the head 35 and 55 forces the mandrel downwardly, thus compressing the spring 34. When the mandrel is depressed the cross bar 47 is lowered, thus permitting the shanks 45 to ride down the guides 48, whereby the cutters 43 are lowered and retracted into the groove 38.

The underreamer is inserted in the upper end of the casing (not shown) and the tool 51, withdrawn. The spring tends to displace the mandrel upwardly whereby the 65 upper portions of the cutters engage the wall

of the casing and ride down the same when the device is lowered into the well. A suitable drilling tool (not shown) may be attached to the lower end of the coupling 27 and lowered into the well in advance of the 70 underreamer. When the hole has been drilled below the casing or the casing is raised, the cutters 43 ride out of the lower end of the casing and are free to expand.

The spring 34 being released elevates the 75 mandrel and the cross bar 47 carries the lugs 46 upwardly. When the lugs are carried upwardly the shanks 45 are elevated in the slots 40. As the shanks move upwardly they ride the inclined walls 41 and are directed inwardly and held snugly in contact with the inner walls of the guides; also the faces 44' are caused to travel in close contact with the faces 36.

When the shanks reach the upper end of 80 their movement they will engage the shoulders 42 and the cutters will bear against the shoulders 37, thus the upward thrust imparted to the cutters will be sustained by the shoulders 37 and 42. The shanks will also 90 fit snugly between the inner walls of the guides 48 and the walls 41 of the slots as well as the side walls of said elements, whereby said shanks will be held against lateral, radial and upward displacement. The 95 faces 44' will also have an ample bearing on the faces 36, so as to resist any crushing strain to which the cutters may be subjected.

It is pointed out that amplified bearing 100 surfaces are had for the cutters and their shanks and these will be amply supported in both their retracted and extended positions as well as during the movement therebetween. When the cutters are forced downwardly any mud or foreign matter will be 105 readily dislodged owing to the inclined ledges 39.

What we claim is:

1. In an underreamer, a stock, a stem depending from the stock, a spring pressed mandrel in the stem, supporting elements surrounding the stem and having curved faces, said elements having slots in said faces, and cutters having inner faces riding on the curved faces and engaging with the mandrel thru the slots of the said elements.

2. In an underreamer, a stock, a stem depending from the stock, a spring pressed mandrel in the stem, supporting elements surrounding the stem and having curved faces, said elements having slots in said faces, cutters having inner faces riding on the curved faces and engaging with the mandrel thru the slots of the said elements, and a drill connecting coupling mounted on the lower end of the stem.

3. In an underreamer, a stock, a stem depending from the stock and having a slot, segmental plates mounted on the stem and having curved faces, said plates having

- slots, guideways in the stem, a mandrel mounted to slide vertically in the stem and stock, and cutters having surfaces contacting with the curved faces of the 5 plates and provided with shanks extending thru the slots of the plates and stem and engaging the mandrel, said cutter shanks riding in the guideways of the stem.
4. In an underreamer, a stock, a stem depending from the stock and having a slot, segmental plates mounted on the stem and having curved faces, said plates having slots, guideways in the stem, a mandrel mounted to slide vertically in the stem 10 and stock, cutters having surfaces contacting with the curved faces of the plates and provided with shanks extending thru the slots of the plates and stem and engaging the mandrel, said cutter shanks riding in 15 the guideways of the stem, and a drill coupling mounted on the stem and supporting 20 the plates.
5. In an underreamer, a stock, a stem depending from the stock, an annular support 25 surrounding the stem and having curved cutter expanding faces, curved guideways on the stem, cutters having curvilinear faces in constant engagement with the expanding faces at all adjustments of said cutters, 30 shanks carried by the cutters and in constant engagement with the guideways, and a spring pressed mandrel for elevating the cutters.
6. In an underreamer, a stock, a stem depending from the stock, an under cut annular socket in the lower end of the stock surrounding the stem, a drill coupling mounted on the lower end of the stem and having a downwardly inclined seat, segmental 35 plates surrounding the stem and having oppositely beveled ends engaging in the socket and the seat, whereby said plates are fastened against movement, said plates having recesses provided with upwardly curved 40 cutter expanding faces, cutters mounted to slide vertically in said recesses and having 45
- faces engaging said expanding faces, and a resiliently sustained mandrel mounted in the stock and stem and engaged by the cutters.
7. In an underreamer, a stock, a stem depending from the stock and having a transverse slot, a spring sustained mandrel mounted to slide in the stock and stem and projecting into the slot of the stem, a pair of segmental plates surrounding the stem and 50 having recesses provided with curved expanding faces, said plates having slots registering with the slot of the stem and extending above the recesses, said stem having vertical guides, and cutters having curvilinear faces engaging the expanding faces in the recesses and provided with shanks extending thru the slots of the plates and the stem and engaging the mandrel the plates having shoulders engaged by the cutter and 55 their shanks to sustain the upward thrust imparted to the cutters.
8. In an underreamer, a stock, a stem depending from the stock and having a transverse slot, a spring sustained mandrel 60 mounted to slide in the stock and stem and projecting into the slot of the stem, a pair of segmental plates surrounding the stem and having recesses provided with curved expanding faces, said plates having slots 65 registering with the slot of the stem and extending above the recesses, said stem having vertical guides, cutters having curvilinear faces engaging the expanding faces in the recesses and provided with shanks extending 70 thru the slots of the plates and the stem and engaging the mandrel, the plates having shoulders engaged by the cutters and their shanks to sustain the upward thrust imparted to the cutters, and a drill connecting 75 the plates in place.
- In testimony whereof we affix our signatures.

JOHN J. BOOKHOUT.
JAMES R. BOOKHOUT.
